United States Patent Office.

HUBERT BURGESS, OF SAN FRANCISCO, CALIFORNIA.

Letters Patent No. 65,165, dated May 28, 1867.

PENCIL-SHARPENER.

The Schedule referred to in these Letters Patent and making part of the same.

TO ALL WHOM IT MAY CONCERN:

Be it known that I, HUBERT BURGESS, of San Francisco, in the county of San Francisco, and State of California, have invented a new and improved Pencil-Sharpener; and I do hereby declare that the following is a full, clear, and exact description thereof, reference being had to the accompanying drawings, forming part of this specification.

The nature of my invention consists in constructing a device by which slate and lead pencils, also crayons, may be sharpened in the most perfect and expeditious manner. It consists more particularly in constructing a small case in which is fitted a small tray, in which is secured a small file upon which the pencil is sharpened after the wood has been cut away.

To enable others skilled in the art to make and use my invention, I will proceed to describe its construction and operation.

Figure 1 is a top plan view of my improved pencil-sharpener.

Figure 2 is a side elevation of the same.

Figure 3 is a transverse sectional elevation of fig. 2.

Letters of like name and kind refer to like parts in each of the figures.

A represents a box or case made of sheet metal, and B a tray, which may be made of the same material, and to fit closely in the case or box A. In this tray B is secured a flat file, C, by soldering or otherwise, upon which the pencil is applied for the purpose of being sharpened. At the front side and ends of this file C is a space for the purpose of receiving the dust as it is filed from the pencil. This tray B is made to slide out and in the case or box A, and when closed makes a neat and compact little device.

This invention is designed for public schools, and by which a child can sharpen its pencil in the neatest and most perfect manner, by simply laying the pencil on the file and letting it rest upon the side of the tray, which serves as a guide; then by moving it alternately back and forth a neat flat point is made. The tray containing the file may be held in the hand or allowed to rest on the desk or table, in the latter case, being much firmer, the file cuts better, and a point is made more quickly. The space around the file is made to contain the dust, rendering the process of sharpening exceedingly simple, expeditious, and perfectly clean. In crayon drawing the constant use of the knife in cutting the points, and the difficulty of the operation, having to cut from the point downward, renders it not only tedious, but filthy in consequence of the dust. The use of my invention entirely obviates the difficulty, rendering it easy, and accomplishing the object without soiling the fingers.

Having thus described my invention, what I claim as new, and desire to secure by Letters Patent, is—

The case or box A, tray B, and file C, for sharpening pencils, substantially as shown and described.

HUBERT BURGESS.
